UNITED STATES PATENT OFFICE.

ROBERT C. RUSSELL, OF PITTSBURGH, PENNSYLVANIA.

CARD INDEX.

Application filed November 14, 1922. Serial No. 600,930.

To all whom it may concern:

Be it known that I, ROBERT C. RUSSELL, a citizen of the United States, and a resident of Pittsburgh, in the county of Allegheny and State of Pennsylvania, have invented certain new and useful Improvements in Card Indexes; and I do hereby declare the following to be a full, clear, and exact description of the invention, such as will enable others skilled in the art to which it appertains to make and use the same.

This invention relates to improvements in card indexes of the visible type and more particularly to means which will operate to protect the free edge portion of the cards, one object of the invention being to provide a protector which may readily and quickly be applied and removably secured to a card of the index and operate to protect the free edge portion of the card from becoming soiled or injured; which may be easily cleaned, and which may also be utilized to hold another or supplemental card.

With this and other objects in view, the invention consists in certain novel features of construction and combinations of parts as hereinafter set forth and pointed out in the claims.

In the accompanying drawings,—

Figure 1 is a rear view of an index showing the application of my improvements thereto.

Figure 2 is a front view of the same.

Figure 3 is a front view of one of the cards and its support with the protector removed.

Figure 4 is a view of a supplemental card.

Figure 5 is a perspective view of the protector.

Figure 6 is a transverse sectional view showing the protector in place on an index card and operating to also attach another or supplemental card to the index card.

Figure 7 is an enlarged detail view illustrating one form of fastening means for the protector to a card, and

Figure 8 is an enlarged detail view showing a different form of fastening means.

In Figures 1, 2 and 3 of the drawing and also in Figure 6, I have shown a combined index card 1 and support 2, the card having hinge connection with the support and the latter provided with lateral tongues 3 to enter guide-ways in a suitable holder not shown. The support member 2 is provided with an upwardly projecting tongue 4 and

a slot 5 is provided for the accommodation of the tongue 4 of another combined device whereby the combined devices may, when assembled in a holder, have interlocking connection with each other. The construction is such that the card member 1 will overlie a portion of the support member 2 and form in effect a shallow pocket 6.

My improved protector 7 is made of flexible and preferably transparent material, such as celluloid and is bent to form approximately parallel members 8 and 9, the latter having greater width than the other. By reason of the flexibility of the material composing the protector 7 it may be caused to grasp the lower portion of the card to which it is applied but this grasping or clip action is not depended upon to retain the protector in place on the card. When the protector is applied to the card, the wider member of the same will preferably be disposed in front of the card and this member is so cut near its respective ends as to provide resilient tongues 10 which will project through openings 11 in the card and may enter notches 12 in the free edge of the rear member 8 of the protector, thus locking said protector to the card but permitting its removal when necessary by merely pressing forward the spring or resilient tongues 10. In the embodiment of the invention shown in Figure 7, each tongue is made approximately V-shape by cutting a V-shaped slot in the material of the protector near each end thereof, thus providing a single spring tongue near each end of the protector. If desired however, two spring tongues such as indicated at 10. Figure 8 may be provided near each end of the protector and the form of the openings in the card and in the back member of the protector may be changed accordingly.

The protector 7 not only serves to guard the card against soiling or injury but it may also be utilized to receive and hold a supplemental card 13 disposed in front of the main card 1 and provided with openings 14 for the passage of the spring tongues of the protector. When a supplemental card is thus mounted on a main card, the upper edge of said supplemental card will enter the shallow pocket 6 formed near the junction of said main card with the support 2 as indicated in Figure 6 and thus the upper portion of the supplemental card will be held in place against the main card 1.

Having fully described my invention what I claim as new and desire to secure by Letters Patent, is:

1. A protector for the edge portion of an index card, consisting of a single piece of resilient material bent upon itself to provide approximately parallel members, one of said members provided intermediate of its ends with a resilient projection which normally projects beyond the face of said member, whereby it may spring into engagement with a shoulder on a card disposed between said members.

2. A protector for the edge portion of an index card, consisting of a single piece of resilient material bent to form two approximately parallel members, one of said members having a tongue to pass through the card and the other member constructed to permit interlocking relation of said tongue thereto.

3. A protector for the edge portion of an index card consisting of a single piece of re-

silient material bent to form two approximately parallel members, one wider than the other, the wider member having inwardly projecting resilient tongues and the narrower member having notches to receive said tongues.

4. The combination with an index card and a support therefor, said support having a part disposed approximately parallel with a portion of the card and cooperating with the latter to form a pocket, of a member engaging the lower or free portion of the card and serving to protect the latter, and a supplemental card supported at one edge by said member and having its other edge portion entering said pocket.

In testimony whereof, I have signed this specification in the presence of two subscribing witnesses.

ROBERT C. RUSSELL.

Witnesses:

ROBERT ALEXANDER DODDS,
BELLE WILHELM.

Certificate of Correction.

It is hereby certified that in Letters Patent No. 1,478,766, granted December 25, 1923, upon the application of Robert C. Russell, of Pittsburgh, Pennsylvania, for an improvement in "Card Indexes," errors appear in the printed specification requiring correction as follows: Page 1, line 30, for the word "rear" read *front*, and lines 33 and 34, for the word "front" read *rear*, and line 102, for the words "in front" read *at the rear*; and that the said Letters Patent should be read with these corrections therein that the same may conform to the record of the case in the Patent Office.

Signed and sealed this 6th day of May, A. D. 1924.

[SEAL.]

KARL FENNING,
Acting Commissioner of Patents.
